UNITED STATES PATENT OFFICE

MILTON TIBBETTS, OF DETROIT, MICHIGAN, ASSIGNOR TO PACKARD MOTOR CAR COMPANY, OF DETROIT, MICHIGAN, A CORPORATION OF MICHIGAN.

GEAR-CUTTING MACHINE.

1,140,012.

Specification of Letters Patent. Patented May 18, 1915.

Specification filed April 7, 1914. Serial No. 830,232.

To all whom it may concern:

Be it known that I, MILTON TIBBETTS, a citizen of the United States, and resident of Detroit, Wayne county, State of Michigan, have invented certain new and useful Improvements in Gear-Cutting Machines, of which the following is a specification.

This invention relates to gear cutting machines and particularly to machines for cutting gears having curved teeth.

The invention consists broadly of blank holding means in combination with a tool holder adapted to operate the tool to cut intermittently.

15 In the embodiment of the invention shown the tool holder is pivotally supported and is oscillated so that the tool passes forth and back across the face of the blank in a curved path, cutting on the forward stroke and being lifted to clear the blank on the return stroke. In this construction also the blank is rotated intermittently in time with the tool operation.

25 The salient object of the invention is to simplify the mechanism of the machines of this type and otherwise improve upon their construction.

Other objects of the invention will be apparent from the following description taken in connection with the drawings, which form a part of this invention, and in which:

Figure 1 is a side elevation, partly in section, of the improved machine; Fig. 2 is a plan view, partly in section, with some of the parts removed, and with the gear blank shown in dotted lines; Fig. 3 is a view similar to Fig. 2, of the left hand end of the machine, showing parts in a different position. Fig. 4 is a section substantially on the line 4—4 of Fig. 2; Fig. 5 is a view showing a second form of tool holder lifting mechanism; Fig. 6 is a section through the blank arbor bearing and spacing head on the line 45 6—6 of Fig. 7; Fig. 7 is a section through the spacing head on the line 7—7 of Fig. 6; Fig. 8 is a similar section, showing the working parts in a different position; Fig. 9 is a top view of the spacing head corresponding to the sections shown in Figs. 7 and 8; and Fig. 10 is an end view of an arbor flange.

In the embodiment of the invention shown in the drawings, the frame or bed of the ma-

chine is indicated at 20, and upon the right end of the frame, as shown in Figs. 1 and 2 is mounted the means for supporting and operating the gear blank. This means intermittently rotates the blank to coöperate with an intermittently operating cutting tool, and rolls the blank on its pitch surface to generate the tooth. It consists principally of a plate 21 mounted upon a flat upper surface 22 of the frame, and having a series of circular grooves 23 in which fit the corresponding circular flanges 24 of a securing plate 25, which is fastened to the frame by the screws 26. The circumference of the plate 21 is formed with gear teeth 27, with which meshes a worm 28 driven by a shaft 29, whereby the plate 21 is rotated or oscillated about a vertical axis which passes through the apex of the former-cone, hereinafter described. The plate 21 carries two uprights 30 between which is adjustably held a block 31 or bearing 31, as by bolts 32. Thus this bearing is adjustable about the apex of the former-cone for operation upon different sized gears or blanks.

The blank 33 is removably clamped to the arbor 34 which operates in the bearing 31, and upon the upper end of the arbor is rotatably mounted the housing 35 of the spacing head, the lower part of this housing comprising the former-cone 36, which is a production of the pitch cone of the blank 33. By means of two steel bands 37, each of which has one end attached to the cone 36 and the other to the body of the machine in such a way that one band prevents the slipping of the cone in one direction and the other in the other direction, the said cone is so held that when the grooved plate 21 is oscillated, the cone will assume a motion as of a cone rolling on a plane without slip. If the housing 35, of which the said cone is a part, were coupled to the blank arbor 34, this rolling motion would be transmitted to the blank 33, thereby imparting to the latter that motion which is necessary to cause the tool to generate the proper tooth contour. As a matter of fact, however, the housing 35 is only intermittently coupled to the arbor 34—namely, during the forward stroke of the tool. During the return stroke of the tool, the blank arbor is rotated in relation to the housing 35 through the distance, preferably, of one tooth of the blank

33. This intermittent rotation is accomplished as follows: Within the housing 35 is rotatably mounted a worm wheel 38, shown in full lines in Figs. 7 and 8 and in dotted lines in Fig. 6, which worm wheel is driven by means of a worm 39, operated by a flexible shaft 40, from the tool operating mechanism in timed relation with the tool, so that the worm wheel 38 will make one-half of a revolution for every full forward and back movement of the tool.

The face of the worm wheel 38 is provided with two rollers 41 and 42, which engage with two grooves 43 and 44, planed at right angles to each other, into the face of a wheel 45. When the worm wheel 38 is in the position shown in Fig. 7, the roller 41 enters the groove 43 and imparts to the wheel 45 a rotary movement of an accelerating nature. After the worm wheel has completed one-eighth of a rotation and assumed the position shown in Fig. 8, it will have imparted to wheel 45 one-eighth of a revolution, and the rate of motion or speed of the wheel 45 will have reached its maximum. As the worm wheel 38 completes another one-eighth of a revolution, the movement imparted to the wheel 45 will be of a retarding nature, and the groove 43 of the wheel 45 will arrive at the position which the groove 44 assumes in Fig. 7, the roller 41 leaving the groove at this time. During the next quarter turn of the worm wheel 38, the wheel 45 will remain stationary until the first semi-revolution of the worm wheel has been completed and the rollers 41 and 42 have exchanged their positions. The roller 42 will then enter the groove 44, which will then be in the position occupied by the roller 41 and the grooves 43 of Fig. 7, and the operation described above will be repeated. In this way, an intermittent motion is imparted to the wheel 45, which is so timed that a quarter rotation occurs during the return stroke of the cutting tool, while the wheel 45 will remain at rest during the forward stroke of said tool. The wheel 45 is secured to an arbor 46, to which is clamped a change-wheel 47. This wheel is geared through an idler 48 to the change-wheel 49, which is clamped to an arbor 50. This arbor carries a flange 51, provided with arc shaped slots 51^a, shown in Fig. 10. By means of bolts 52 which pass through said slots the spacing pinion 53 is adjustably secured to the arbor 50. This pinion engages with the master wheel 54, which is secured to the blank arbor 34. Thus the train of gears just described connects the groove wheel 45 with the blank arbor 34. The change gears are so selected that for each quarter revolution of the wheel 45, the blank 33 is rotated through the space of one tooth.

65. For holding the blank firmly during the

forward stroke of the tool, an anchor is provided as follows: To the arbor 55 of the worm wheel 38, is secured a cam 56, Fig. 9, which engages with the cam roller 57 of the anchor lever 58, the spring 59 holding the roller in contact with the cam. The lever 58 carries the anchor-toe 60, engaging with the notched anchor wheel 61, which is clamped to the pinion arbor 50. The cam 56 is so timed that the wheel 61 will be anchored during the forward stroke of the tool and released during the return stroke, these strokes of the tool being more fully hereinafter described. The tool T is shown in the various figures as of the usual rack tooth form and it is so mounted and operated that it oscillates or passes intermittently in a curved path crosswise the face of the blank. Preferably, the intermittent operation of the tool is such that it cooperates with the spacing mechanism of the blank holding and operating means whereby the tool passes across the face of the blank on its cutting stroke while the blank is held stationary and returns to initial position as the blank is rotated one or more tooth spaces. The means for supporting and operating the tool comprises a support 130 pivoted on a vertical axis 131 and provided with a tool holder 132 which is pivoted at 133 to the support 130. The axis 131 is an adjustable one and is shown as movable in a substantially horizontal plane and in an arc having a general direction making an angle to a vertical plane substantially 100 through the axis of the gear blank. The bracket 134 in which the support 130 is supported, is movably mounted on the frame 20, and adjusted by the adjusting screws 135. Screws 136 secure the bracket in adjusted position. This construction is shown in section in Fig. 4.

It will be understood that the support 130 is adapted to oscillate about the axis 131 thus causing the tool which it supports 110 and operates to move in a curved path in the arc of a circle, the radius of the arc depending upon the position of the tool relative to the axis 131. This distance is made adjustable by varying the length of 115 the support 130 by manipulating the bolt and slot connection 137 shown clearly in Figs. 1 and 2. Suitable means are provided for oscillating the support 130 and in the embodiment of the invention shown, this 120 means comprises a connecting rod 138 operated by a crank pin 139 on a shaft 140, which shaft in turn is operated through bevel gearing 141 by the driving shaft 142. The crank pin 139 is preferably adjustable 125 in the slot 143 of disk 144 as shown to vary the stroke of the tool or the degree of oscillation of the support 130. The disk 144 is also formed with gear teeth 145 meshing with a pinion 146 on the flexible shaft 40, 130

above described, for driving the latter. As the blank is adapted to be rotated a tooth space during the return or non-cutting stroke of the tool while at the same time it is retained in the cutting path of the tool, the latter is raised from cutting position on said return stroke, and suitable means are herein provided for thus raising the tool. The tool is shown as yieldingly held in its normal or cutting position by a spring 147, and in the form of the invention shown in Figs. 2 and 3, the tool holder 132 is adapted to be raised from normal position by means of a push rod 148 mounted in suitable lugs 149 and acting upon a pin 150 secured in the holder. The push rod 148 is operated directly by a cam 151 on an arm 152 forming an extension of the connecting rod 138. Thus it will be seen that as the support 130 reaches the forward end of its stroke, the connecting rod 138 is moved laterally and the cam 151 operates to push the push rod 148 lengthwise and act upon the pin 150 to raise the tool holder 132 from its normal position to such position that the tool will clear the blank upon the return stroke. The connecting rod 138 again moves laterally at the end of the return stroke of the support 130 so that the tool holder again assumes normal position for the cutting stroke.

Another form of tool holder lifting mechanism is illustrated in Fig. 5. In this case an arm 153 is directly keyed to the pivot 133 of the tool holder 132, and this arm 153 is acted upon directly by the cam 151 hereinabove described. This construction gives the same results as that shown in Figs. 1, 2 and 3.

It will be understood that the invention is not limited to the specific form of the machine shown herein, but is capable of modification in various ways without departing from the scope of the claims.

Having thus described my invention, what I claim and desire to secure by Letters Patent is:—

1. In a gear cutting machine, in combination, means for supporting the blank, a tool support, means for oscillating the tool support so as to move the tool in a path concentric to the axis of oscillation to shape the tooth, and means for producing a relative movement between the blank and tool to generate the tooth.

2. In a gear cutting machine, in combination, means for supporting the blank, a pivotally mounted tool support, means for oscillating the tool support upon and concentric to its pivot to provide the cutting movements of the tool, and means for producing a relative movement between the blank and the tool to generate the tooth.

3. In a gear cutting machine, in combination, means for supporting the blank, a pivoted tool support, and means for oscillating

the tool support upon and concentric to its pivot comprising an eccentric and connecting rod mechanism.

4. In a gear cutting machine, in combination, means for supporting the blank, a pivoted tool support, and means for oscillating the tool support on its pivot comprising a shaft parallel with the pivot of said tool support, an eccentric on said shaft, and a connecting rod connecting said eccentric and the tool support.

5. In a gear cutting machine, in combination, means for supporting the blank, a tool support, a tool holder pivoted on said support, means for oscillating the tool support so as to move the tool in a path concentric to the axis of oscillation to cut the tooth, and means operated by said oscillating means for lifting the tool holder on the return oscillating stroke of the support.

6. In a gear cutting machine, in combination, means for supporting the blank, a tool support, a tool holder pivoted on said support, means for oscillating the tool support so as to move the tool in a path concentric to the axis of oscillation to cut the tooth, and a finger moved by said oscillating means for lifting the tool holder on the return oscillating stroke of the support.

7. In a gear cutting machine, in combination, means for supporting the blank, a tool support, a tool holder pivoted on said support, means for oscillating the tool support comprising an eccentric and connecting rod mechanism, and an extension on said connecting rod for lifting the tool holder on alternate oscillating strokes of the support.

8. In a gear cutting machine, in combination, means for supporting and intermittently rotating the blank on its axis, a tool support, means for oscillating the tool support so as to move the tool in a path concentric to the axis of oscillation to cut the gear, the oscillations being in time with the intermittent rotary motion of the blank, and means for producing a relative movement between the blank and the tool to generate the tooth.

9. In a gear cutting machine, in combination, means for supporting and intermittently rotating the blank on its axis, a pivotally mounted tool support having a tool which moves in a path concentric to the pivot of the support, means for moving the tool support on its pivot and causing the tool to make intermittent cutting strokes across the face of the blank in time with the intermittent motion of the blank, and means for producing a relative movement between the blank and the tool to generate the tooth.

10. In a gear cutting machine, in combination, means for supporting the blank, a tool support mounted to move bodily about

- an axis, a tool mounted on said support, means for moving the tool support about its axis to cause the tool to make intermittent cutting strokes in a path concentric to the axis of the support, means for rotating the blank a tooth space after each of said cutting strokes of the tool, and means producing a relative movement between the blank and tool to generate the tooth.
10. 11. In a gear cutting machine, in combination, means for supporting the blank, a tool support mounted to move bodily about an axis, a tool mounted on said support, means for moving the tool support about its axis to cause the tool to make intermittent cutting strokes in a path concentric to the axis of the support, means for rotating the blank intermittently a tooth space at a time without changing the relation of the axis of the blank to the axis of the tool support except as the relation of said axes may be changed by the generation of the tooth, and means producing a relative movement between the blank and tool to generate the tooth.
12. In a gear cutting machine, in combination, means for supporting the blank, a tool support mounted to move bodily about an axis, a tool mounted on said support, means for moving the tool support about its axis to cause the tool to make intermittent cutting strokes in a path concentric to the axis of the support, means for rotating the blank intermittently a tooth space at a time while retaining the blank in the cutting path of the tool, said rotation of the blank being in timed relation to the movement of the tool support, and means producing a relative movement between the blank and tool to generate the tooth.
13. In a gear cutting machine, in combination, means for supporting the blank, a tool support mounted to move about an axis, a tool mounted on said support, means for oscillating the tool support to cause the tool to make intermittent cutting strokes in a path concentric to the axis of the support, means for rotating the blank intermittently a tooth space at a time while retaining it in the cutting path of the tool, means for lifting the tool on alternate oscillating strokes of the support to clear the blank, and means for producing a relative movement between the blank and tool to generate the tooth.
14. In a gear cutting machine, in combination, means for supporting the blank, a pivoted tool support and tool thereon arranged to move in a path concentric to the axis of the support, adjusting means for varying the radial position of the tool relative to the support pivot, and means for moving the tool support on its pivot to effect the cut in the blank.
15. In a gear cutting machine, in combination, means for supporting the blank, an oscillatory tool support and tool thereon arranged to move in a path concentric to the axis of the support, said support comprising means for adjusting the relative position of the tool and support pivot, and means for operating the tool support on its pivot to effect the cut in the blank.
16. In a gear cutting machine, in combination, means for supporting the blank, a pivoted tool support and tool thereon arranged to move in a path concentric to the axis of the support, means for oscillating the tool support to effect a cut, and a device moved by said oscillating means for lifting the tool on the return oscillating stroke of the support.
17. In a gear cutting machine, in combination, means for supporting the blank, a tool support, a tool holder pivoted on said support, an arm keyed to the pivot of said holder, means for oscillating the support so as to move the tool in a path concentric to the axis of oscillation of the support, and a device moved by said oscillating means for contacting said arm and turning said holder on its pivot.
18. In a gear cutting machine, in combination, means for supporting the blank, a tool support, a tool holder keyed to a horizontal pivot on said support, said pivot having an arm, means for oscillating the support comprising a crank and connecting rod, and a cam on said connecting rod adapted to operate on said arm at the end of its stroke to turn the holder on its pivot and lift the tool on alternate strokes of the support.
19. In a gear cutting machine, in combination, means for supporting the blank, a pivoted tool support and tool thereon arranged to move in a path concentric to the axis of the support, adjusting means for varying the radial position of the tool relatively to the support pivot, adjusting means for varying the position of the support pivot relatively to the blank, and means for moving the tool support on its pivot to effect the cut in the blank.
20. In a gear cutting machine, in combination, means for supporting the blank, a pivoted tool support and tool thereon arranged to move in a path concentric to the axis of the support, adjusting means for varying the radial position of the tool relatively to the support pivot, means for adjusting the support pivot toward and away from the axis of the blank, and means for moving the tool support on its pivot to effect the cut in the blank.
21. In a gear cutting machine, in combination, means for supporting the blank, a pivoted tool support and tool thereon ar-

ranged to move in a path concentric to the axis of the support, adjusting means for varying the radial position of the tool relatively to the support pivot, means for adjusting the support pivot in a substantially horizontal plane and in an arc having a general direction making an angle to a vertical plane passing substantially through the axis of the gear blank, and means for moving

the tool support on its pivot to effect the cut in the blank.

In testimony whereof I affix my signature in presence of two witnesses.

MILTON TIBBETTS.
